UNITED STATES PATENT OFFICE.

ALFRED M. ROWE, OF CHICAGO, ILLINOIS.

FEED-WATER HEATER.

SPECIFICATION forming part of Letters Patent No. 468,181, dated February 2, 1892.

Application filed October 23, 1890. Renewed July 6, 1891. Serial No. 398,467. (No model.)

To all whom it may concern:

Be it known that I, ALFRED M. ROWE, a citizen of the United States, residing at Chicago, in the county of Cook and State of Illinois, have invented a certain new and useful Improvement in Feed-Water Heaters, of which the following is a specification.

My invention relates to that class of feed-water heaters shown and described in Patent No. 359,634, granted to myself March 22, 1887.

In addition to the objects of the improvement set forth in my said patent, the objects of this improvement are to provide a scum-chamber, by means of which the scum and light particles that rise to the top of the water-chamber can be effectively removed; to provide a settling-chamber having an increased capacity for permitting the collection of sediment from the feed-water without obstructing the inlet and without necessitating the objectionable feature of blowing off the sediment; to provide a heater having a series of pipes, through which the water can circulate, and which present a maximum amount of surface, which is subject to the heating action of the exhaust-steam, whereby the greatest amount of water can be heated to a high temperature in a short time; to provide means whereby the circulating-pipes are subjected to the action of the exhaust-steam on all sides, so as to avoid the loss of heat by radiation; to provide a heater of the kind described of simple, inexpensive, and durable construction, and to provide certain novel and improved features of construction tending to general efficiency and utility of the apparatus.

My invention consists in the features of construction and combination of parts hereinabove fully described, and pointed out in the appended claims.

In the accompanying drawings, Figure 1 is a view of a feed-water heater constructed in accordance with my invention, and is partly in central vertical section and in side elevation. Fig. 2 is a transverse section of the same on line 22 of Fig. 1.

The steam-chamber A, which is formed within a suitable shell or casing A', is provided at its side and at its lower end with a steam-inlet A². The exhaust or discharge outlet A³ is arranged at the side of the casing

above the inlet A² and conveniently diametrically opposite thereto.

The system of return water-pipes, herein shown as contained within the steam-chamber, is as follows: An ordinary water-conducting pipe b, which in practice is connected with a suitable source of water-supply, enters the steam-chamber at the upper portion of the latter, and shortly after its entrance into said chamber is expanded to provide or is connected with a pipe or chamber B, which extends downwardly through the steam-chamber, and which may be regarded as an enlarged water-supply pipe or water-supply chamber. The water-supply pipe or chamber B is by preference arranged centrally within the steam-chamber, in order that the water therefrom may be more conveniently distributed to one or more series of return water-pipes, which are in communication with the lower portion of the supply pipe or chamber B and which stand around the same. The said return water-pipes, which thus communicate at their lower ends with the supply pipe or chamber B, rise from the lower portion of the steam-chamber and are at their upper ends placed in communication with a discharge-pipe C, which is common to all of said return-pipes and which serves as a means for feeding the heated water to a boiler.

As a means for placing the water-supply pipe or chamber B in communication with return water-pipes, said supply pipe or chamber is at its lower end connected with a water-chamber D, with which latter the upwardly-extending return-pipes are connected. This chamber D not only serves as an efficient means for supplying the said upwardly-extending return-pipes, but being arranged at the base of said apparatus it also provides a desirable settling-chamber, having a capacity which permits the accumulation of considerable sediment without rendering it necessary to frequently blow off the sediment which has accumulated therein. In order to promote the efficiency of chamber D for the last-named purpose, it is provided with a suitable hand-hold plate D' or the like, whereby access may be had to it when so desired. In order to place the said return water-pipes in communication with the discharge-pipe C, all

of said pipes are desirably connected with an annular water-chamber E, arranged within and at the upper portion of the steam-chamber A. By such arrangement the pipe b can 5 be extended down through the space e, which is bounded by said annular chamber. The return-pipes, which are connected at their lower ends with the lower water-chamber D and at their upper ends connected with the 10 upper water-chamber E, are desirably arranged around the water-supply pipe or chamber B, so as to constitute three sets, the pipes F F' F², composing said sets, being either arranged to form annular concentric 15 series, as in Fig. 2, or irregularly distributed, as may be desired.

The steam-chamber A is separated from the lower water-chamber D by means of a circular partition or diaphragm A⁴, which 20 rests at its outer edge upon an annular flange a, which extends inwardly from the casing A' and is located just below the inlet A². The said diaphragm A⁴ is provided centrally with an aperture for the supply pipe or chamber 25 and with sets of apertures for the return water-pipes F F' F², whereby all of said water-pipes communicate with the water-chamber D. The outer set of pipes F² of said annular 30 series are separated from the two sets F and F', which are located nearest the supply pipe or chamber B by an inner cylindric shell or casing A⁵, extending from a point near the upper ends of said pipes to a point horizontally between the inlet and outlet passages 35 A² and A³ and located between the sets of pipes F² and F'. In this way an annular chamber a', extending nearly the height of the steam-chamber, is formed between the inner wall of the steam-chamber and the inner 40 shell or casing A⁵, in which chamber a' the pipes F² are located. The main steam-chamber A is by this arrangement divided for the greater portion of its length into two communicating chambers a' and a², the latter being 45 the larger of the two and containing two sets of pipes F' and F and being directly connected with the source of steam-supply. The inner shell or casing A⁵ is secured upon an inwardly-projecting annular flange A⁶, which 50 is located horizontally between the inlet and outlet passages A² and A³ and extends inwardly from the casing A' to a point between the sets of pipes F² and F', the pipes F² passing 55 through apertures in said flange and having steam-tight connections therewith.

In the particular construction illustrated the casing A embraces an upper section a³ and a lower section a⁴, which are riveted together in a familiar manner, while a flat ring 60 forming the flange A⁶ is held between the adjacent ends of said upper and lower sections a³ and a⁴.

The upper water-chamber E is provided with an upwardly-extending portion E', forming 65 a scum-chamber, and in the construction illustrated said scum-chamber embraces an approximately semi-spherical cap extending

above said water-chamber E. A blow-off pipe e' leads from the upper portion of said scum-chamber. It will be obvious that any scum and light particles that may rise to the top of the water-chamber E will be collected in the scum-chamber E', and to prevent any of such matter passing out through the water-discharge pipe C the latter extends some distance downwardly into the water-chamber E, so that its intaking end will be below the level whereat the scum accumulates.

Steam entering through the inlet A² is first received within the larger subdivision a² of 80 the steam-chamber, in which said subdivision the steam circulates upward and around the pipes F and F' exposed therein, and from thence a portion of it passes through the space or passage e, formed by the annular 85 chamber E, so as to reach the upper portion of the steam-chamber, from whence it passes downwardly through the annular chamber or annular subdivision a' of the steam-chamber A to the exhaust-outlet A³. The steam that 90 does not pass out through the passage e passes over the top of the inner shell or casing, and then down through the annular subdivision a² to the said exhaust-outlet A³.

By the foregoing arrangement the steam is 95 equally distributed over the surface of all of the water-pipes, and since it circulates first from one end of the heater to the other and then back to a point adjacent to the inlet end of the steam-chamber the full value of the 100 steam is utilized.

It will be observed that by the arrangement of return water-pipes I obtain a circulation of water from one end of the heater to the other, and then back to the end of the 105 heater at which it first entered, thereby insuring its becoming properly heated. It will also be seen that the feed-water is not in contact with the outer shell of the heater, as in cases where the water-chamber is formed by 110 said shell and steam-pipes submerging in the water, and hence by my arrangement there is no liability of the feed-water becoming cool by contact with the said shell or casing. The large chamber or subdivision a² of the steam-chamber permits the expansion of the exhaust 115 steam which enters through inlet A², whereby there is an absolute freedom from back-pressure.

It is observed that a water-inlet pipe b, the 120 blow-off pipe e', and the pipe C, which is to be connected with a boiler and which will usually have a safety-valve, all extend up through suitable stuffing-boxes at the top of the steam-chamber, in which way the pipes or tubes confined within the steam-chamber will not, by reason of longitudinal expansion or contraction, work loose at their point of connection with the top chamber D, that forms a bottom for the subdivisions of the steam-chamber, it being obvious that the pipes can be fitted so as to be susceptible of a desirable 125 latitude of end movement through their respective stuffing-boxes.

A⁷ indicates a pipe provided with a stop-cock and communicating with the lower end of the steam-chamber A, by means of which any water due to the condensation of the steam may be drawn off.

A⁸ indicates a blow-off pipe communicating with the settling-chamber.

What I claim as my invention is—

1. A feed-water heater comprising the inner and outer steam-chambers, a water-supply pipe or chamber passing through said inner steam-chamber and communicating with a water-chamber located below said steam-chambers, a series of water-pipes located within said steam-chamber and communicating with said water-chamber, and an exhaust inlet and outlet located above said water-chamber.

2. A feed-water heater comprising an outer casing A, an inner casing A⁵, an annular flange A⁶, extending inwardly from said outer casing and joined to said inner casing, whereby the inner and outer steam-chambers are formed which communicate at their upper ends, a series of water-pipes arranged within said steam-chambers, an exhaust-inlet communicating with said inner steam-chamber below said partition, and an exhaust-outlet communicating with the lower portion of said outer steam-chamber.

3. A feed-water heater comprising an outer casing A, a diaphragm near the lower end

thereof for providing a water-chamber D, an inwardly-projecting flange located upon said outer casing above said diaphragm, an inner casing joined at its lower end to said flange and extending nearly to the top of said outer casing, a water-supply pipe or chamber passing through said inner casing and communicating with the water-chamber, a series of water-pipes arranged within said outer and inner casing and communicating with said water-chamber, an exhaust-inlet connected with the outer casing between said diaphragm and flange, and an exhaust-outlet connected with said outer casing above said flange.

4. In a feed-water heater, a series of water-pipes communicating at their upper ends with a water-chamber having an upwardly-extending portion forming a scum-chamber, and a blow-off pipe.

5. In a feed-water heater, a series of water-pipes communicating at their upper ends with a water-chamber having an upwardly-extending portion forming a scum-chamber, a blow-off pipe, and a water-discharge pipe communicating with said water-chamber and extending downwardly into the same.
